UNITED STATES PATENT OFFICE

RUDOLPH FROELICH, OF HALSTEAD, KANSAS

AIR HEATER

Application filed January 17, 1930. Serial No. 421,440.

The present invention relates to an air heater and especially to that class of heaters which are employed for heating residences and other buildings.

5 The prime object of the invention resides in the provision of a heater of this nature wherein a forced draft of air is created therein and heated to be passed out therefrom into the room or the like.

10 Another very important object of the invention resides in the provision of an air heater of this nature which is exceedingly simple in its construction, inexpensive to manufacture, compact and convenient in its 15 arrangement of parts, strong and durable, thoroughly efficient and reliable in use and operation, and otherwise well adapted to the purpose for which it is designed.

With the above and numerous other objects 20 in view as will appear as the description proceeds, the invention resides in certain novel features of construction, and in the combination and arrangement of parts as will be hereinafter more fully described and claimed.

25 In the drawing:

Figure 1 is a perspective view of the air heater embodying the features of my invention, looking at the front thereof,

Figure 2 is a similar view looking at the 30 rear thereof,

Figure 3 is a vertical longitudinal section therethrough,

Figure 4 is a top plan view of the base frame with the heating element mounted 35 therein, taken on the line 4-4 of Figure 3.

Figure 5 is a vertical transverse section taken substantially on the line 5-5 of Figure 3,

Figure 6 is a vertical transverse section 40 taken substantially on the line 6-6 of Figure 3, and

Figure 7 is a horizontal section taken substantially on the line 7-7 of Figure 3.

Referring to the drawing it will be seen 45 that the numeral 5 denotes a rectangular base frame supported on suitable legs 6 and having at its upper edge an inwardly directed flange 7.

A rectangular casing 8 comprises four 50 walls rising from the base frame 5 and is

formed at its bottom edges with inwardly directed flanges 9 to rest on flange 7. A removable hollow top 10 is mounted on the upper edges of the walls of the casing. An inner compartment 11 is formed by a pair of longitudinally extending walls 12 spaced inwardly from the side walls of the casing 8 and extending between the walls thereof in spaced relation to each other and having formed on their bottom edge a curved bottom or hot plate 14.

A top plate 15 is mounted between the upper ends of the walls 12. A baffle or partition plate 16 extends from one end wall inwardly terminating a distance from the other end wall. This baffle 16 has a depression 17 formed therein adjacent one end wall of the casing for the purpose of containing water or the like.

An opening is provided in one end wall 70 between the top plate 15 and the baffle plate 16 and a reticulated door 19 is hingedly mounted to the casing 8 over the opening. The bottom portion of the other end wall is provided with an opening of circular construction having a reticulated sheet 20 thereacross and an inwardly extending cylindrical member 21 in which is located an electric motor 22 and a fan 23 for the purpose of sucking air into the compartment 11 and forcing 80 said air over the hot plate 14 and then up under the baffle and then over the baffle as is indicated by arrows 25 and 26 and finally pass over the water in the depression 17 and out through the reticulated door 19 into the 85 room.

A supporting bar 28 extends longitudinally in the base frame 5 and supports a plurality of gas burners 29 access to which may be had through a door 30 in the front side of the base 90 frame. A suitable control 31 such as a rheostat or the like is provided on the outside of the casing for controlling the speed of the motor 22 and the fan 23.

From the above detailed description it will 95 be seen that the gas burners will effectively heat the hot plate and the gases of combustion may escape between the rear wall 12 and the adjacent wall of the casing 8 through an opening 34 in the rear of the casing having 100

an annular flange 35 so that a stove pipe or the like may be engaged therewith to take these gases off to the exterior of the building or the like.

5 The heating of the hot plate, of course, heats the air inside the compartment 11 and by means of the fan a new supply of air is constantly being injected into the compartment 11 and finally ejected therefrom so that heated fresh air is ejected into the room for efficient and effective heating.

10 It is thought that the construction, operation, utility and advantages of this invention will now be quite apparent to those skilled in 15 this art without a more detailed description thereof.

15 The present embodiment of the invention has been disclosed in detail merely for the purposes of exemplification since in actual 20 practice it attains the features of advantage enumerated as desirable in the statement of the invention and the above description.

25 It is apparent that changes in the details of construction, and in the combination and arrangement of parts may be resorted to without departing from the spirit or scope of the invention as hereinafter claimed or sacrificing any of its advantages.

Having thus described my invention, what 30 I claim as new is:

35 1. An air heater of the class described comprising a rectangular base frame, a rectangular casing rising from the base frame and resting thereon, a top on the casing, one end wall of the casing having an opening in the upper portion thereof and the other end wall of the casing having an opening in the bottom thereof, a pair of longitudinal walls mounted in the casing in spaced relation to the side walls and in spaced relation to each other to form an air compartment, a hot plate curved bottom on the lower edges of the longitudinal walls, a top wall on the longitudinal walls, a baffle wall extending between the upper portions of the longitudinal walls from the said one end wall and terminating a distance from the other end wall of the casing, and burners mounted in the base frame under the hot plate.

40 2. An air heater of the class described comprising a rectangular base frame, a rectangular casing rising from the base frame and resting thereon, a top on the casing, one end wall of the casing having an opening in the upper portion thereof and the other end wall of the casing having an opening in the bottom thereof, a pair of longitudinal walls mounted in the casing in spaced relation to the side walls and in spaced relation to each other to form an air compartment, a hot plate curved bottom on the lower edges of the longitudinal walls, a top wall on the longitudinal walls, a baffle wall extending between the upper portions of the longitudinal walls from the said one end wall and termin-

45 nating a distance from the other end wall of the casing, burners mounted in the base frame under the hot plate, and a motor operated fan mounted in the casing adjacent the opening in said other end wall for sucking air inwardly therethrough.

50 3. An air heater of the class described comprising a rectangular base frame, a rectangular casing rising from the base frame and resting thereon, a top on the casing, one end wall of the casing having an opening in the upper portion thereof and the other end wall of the casing having an opening in the bottom portion thereof, a pair of longitudinal walls mounted in the casing in spaced relation to the side walls and in spaced relation to each other to form an air compartment, a hot plate curved bottom on the lower edges of the longitudinal walls, a top wall on the longitudinal walls, a baffle wall extending between the upper portions of the longitudinal walls from the said one end wall to terminate a distance from the other end wall of the casing, burners mounted in the base frame under the hot plate, a motor operated fan mounted in the casing adjacent the opening in said other end wall for sucking air inwardly therethrough, and a cylindrical member about said fan.

55 4. An air heater of the class described comprising a rectangular base frame, a rectangular casing rising from the base frame and resting thereon, a top on the casing, one end wall of the casing having an opening in the upper portion thereof and the other end wall of the casing having an opening in the bottom thereof, a pair of longitudinal walls mounted in the casing in spaced relation to the side walls and in spaced relation to each other to form an air compartment, a hot plate curved bottom on the lower edges of the longitudinal walls, a top wall on the longitudinal walls, a baffle wall extending between the upper portions of the longitudinal walls from the said one end wall to terminate a distance from the other end wall of the casing, burners mounted in the base frame under the hot plate, a motor operated fan mounted in the casing adjacent the opening in said other end wall for sucking air inwardly therethrough, a cylindrical member about said fan, and a reticulated sheet across the opening in said other end wall.

60 5. An air heater of the class described comprising a rectangular base frame, a rectangular casing rising from the base frame and resting thereon, a top on the casing, one end wall of the casing having an opening in the upper portion thereof and the other end wall of the casing having an opening in the bottom thereof, a pair of longitudinal walls mounted in the casing in spaced relation to the side walls and in spaced relation to each other to form an air compartment, a hot plate curved bottom on the lower edges of the lon-

5 gitudinal walls, a top wall on the longitudinal walls, a baffle wall extending between the upper portions of the longitudinal walls from the said one end wall to terminate a distance from the other end wall of the casing, burners mounted in the base frame under the hot plate, a motor operated fan mounted in the casing adjacent the opening in said other end wall for sucking air inwardly therethrough, 10 a cylindrical member about said fan, and a reticulated sheet across the opening in said other end wall, said casing having formed on its under edge inwardly extending flange to rest on inwardly extending flange formed on the upper edges of the base frame.

15 6. An air heater of the class described comprising a rectangular base frame, a rectangular casing rising from the base frame and resting thereon, a top on the casing, one end wall of the casing having an opening in the upper portion thereof and the other end wall of the casing having an opening in the bottom thereof, a pair of longitudinal walls mounted in the casing in spaced relation to the side walls and in spaced relation to each other to form an air compartment, a hot plate curved bottom on the lower edges of the longitudinal walls, a top wall on the longitudinal walls, a baffle wall extending between the 20 upper portions of the longitudinal walls from the said one end wall to terminate a distance from the other end wall of the casing, burners mounted in the base frame under the hot plate, a motor operated fan mounted in the 25 casing adjacent the opening in said other end wall for sucking air inwardly therethrough, a cylindrical member about said fan, and a reticulated sheet across the opening in said other end wall, said casing having formed on its under edge inwardly extending flange to rest on inwardly extending flange formed on the upper edges of the base frame, and a longitudinal bar in the base frame for supporting the burner.

30 7. An air heater of the class described comprising a rectangular base frame, a rectangular casing rising from the base frame and resting thereon, a top on the casing, one end wall of the casing having an opening in the upper portion thereof and the other end wall of the casing having an opening in the bottom thereof, a pair of longitudinal walls mounted in the casing in spaced relation to the side walls and in spaced relation to each other to 35 form an air compartment, a hot plate curved bottom on the lower edges of the longitudinal walls, a top wall on the longitudinal walls, a baffle wall extending between the upper portions of the longitudinal walls from the said one end wall to terminate a distance from the other end wall of the casing, burners mounted in the base frame under the hot plate, a motor operated fan mounted in the 40 casing adjacent the opening in said other end wall for sucking air inwardly therethrough,

70 a cylindrical member about said fan, and a reticulated sheet across the opening in said other end wall, said casing having formed on its under edge inwardly extending flange to rest on inwardly extending flange formed on the upper edges of the base frame, and a longitudinal bar in the base frame for supporting the burner, said baffle being formed with a depression for containing water adjacent the opening in said one end wall.

75 In testimony whereof I affix my signature.
RUDOLPH FROELICH.
